UNITED STATES PATENT OFFICE

MARDEN C. HUTTO, OF DETROIT, MICHIGAN.

COMBINED ABRASIVE AND CARRIER.

Application filed December 11, 1926 Serial No. 154,280.

This invention relates to abrasive holders for cylinder grinders and is a continuation in part of my application Serial No. 661,883, filed September 10, 1923.

- 5 More particularly the invention is a combined abrasive and holder, the fundamental characteristics of which are described in the said previous application and an improved form of which is disclosed herein.
- 10 The object of the invention is to provide a combined holder and abrasive in which the abrasive member, usually in the form of a natural or artificial stone is supported in a channeled member having associated therewith members engaged by the adjusting means of the tool of which it forms a part so that the grinding face of the abrasive is mounted in the tool in a precise relationship with the adjusting device. In the tool 15 with which the combined abrasive and holder is used as shown in the said original application Serial No. 661,883 and as is shown herein several abrasive members are mounted in a head intended to be reciprocated and 20 rotated in the cylindrical aperture to be ground, and a feature of this invention relates more particularly to the holder of channel like form in which the stone is secured by a self-hardening material—that is, 25 flowed to place in a more or less liquid form. This material may be solder or lead or even a varnish or shellac and, while the stone and holder are held in the relative final positions, the material for securing the stone 30 in place is supplied thereto.

A further feature of the invention is in the provision of a holder of sheet metal form with which the portions thereof adapted for engagement with the adjusting device of the tool are riveted in place and the stone mounted therein by a solder or suitable material in which the stone is "floated" or flowed in its final relationship with the holder and thus fixed in predetermined position as the material hardens.

45 As is hereinafter more fully described I preferably utilize a pair of pins each adjacent an end of the holder which when in the tool fit against opposing coned members that are adjustable toward or from each other and in order that all the holders and the faces of all the abrasives shall lie in the same circle, it is essential that these cone 50 contacting portions, which may be the pins

as shown, shall be of a certain length relative to the grinding face of the stone. Thus the method of manufacture of the abrasive and its holder as hereinafter described seeks primarily to insure accuracy in the mounting of the stone so that the face which lies longitudinally of the tool shall normally be strictly parallel with the axis thereof.

55 Stones used in cylinder grinders orlapping devices are usually made of compacted granular material such as carborundum or like abrasive and subsequently fired. Such stones usually vary in thickness throughout their length and therefore require dressing after the stone has been mounted in its holder.

60 A feature of this invention is in providing a holder and a method of mounting the stone therein which insures parallelism of the grinding face of the stone with the axis of the tool in which it is to be used 65 irrespective of variations in thickness of the stone. Thus, the surface of the stone is normally exactly parallel with the axis of rotation of the grinding dome.

70 An object of this invention therefore is to provide a holder and a stone in which the holder and the stone are held in the desired final relationship and a self-hardening material flowed between the members whereby they automatically become fixed in the necessary relationship and the finishing of the stone 75 subsequent to mounting is dispensed with inasmuch as major inaccuracies are compensated for by the self-hardening material.

75 These objects and the several novel features of the invention are hereinafter more fully described and claimed, and the preferred form of an abrasive and its carrier or holder embodying my invention is shown 80 in the accompanying drawings in which—

85 Fig. 1 is a longitudinal section of a tool showing my improved abrasive and its holder mounted therein.

90 Fig. 2 is a perspective view of the finished holder.

95 Fig. 3 is a cross section taken on line 3—3 of Fig. 2.

100 Fig. 4 is a cross section of the holder and the stone indicating the method of securing the stone in place therein.

105 Figs. 5 and 6 are vertical longitudinal sections, on a reduced scale, taken on the correspondingly numbered lines in Fig. 2,

the self hardening material being shown between the supporting base and the stone corresponding to Fig. 3.

In my previous application Serial No. 5 661,883 above mentioned I have shown a similar holder in which the stone is held in place by means of lead. In the invention there disclosed and herein further described the holder consists of a supporting base having preferably the form of a shell or channeled member 1 which as here shown is preferably made of sheet metal formed in a die and may be provided with an extending lip or lug 2 at opposite ends thereof. This 10 shell or channeled member 1 preferably has a shape in cross section as shown more particularly in Fig. 3 and adjacent each end thereof is provided parallel pins 3 and 4 of like form projecting transversely from the bottom 1^a of the holder and at right angles thereto. These pins extend through apertures provided therefor in the body 5 of the tool to engage the respective cone members 6 and 7, the ends of the pins being tapered 15 as at 8 to provide line contact with the respective cone member. As described in the said previous application these cones may be adjusted as to distance apart through the central adjusting screw 9 which is provided 20 with a head 10 slotted for use of a screw driver. By turning the adjusting screw to draw the cones together the faces of the abrasive members are moved to a greater radial distance from the axis of the tool and 25 by the reverse turning of the screw the cones are retracted which is preferably accomplished through use of the spring members 9^a and 10^a which engage the lips 2 of each of the holders tending to contract the same.

30 The two cones are yieldingly held apart by a spring 9^b surrounding the screw 9 and bearing against the inner ends of the cones, as shown in Fig. 1.

Subsequent to the formation of the channel member by means of a die as stated, the shouldered pins 3 and 4 have the reduced portions 11 thereof inserted through apertures provided adjacent each end of the shell or member 1 and the ends thereof peened over to fixedly secure the pins in place. Upon completion of this step the holder consists of the assembled channeled member and pins which are maintained in fixed relation with the shell but it is to be understood that 45 the channel member may be provided with means for contacting the cones other than what is here termed "pins." Such different form of holder is shown in my pending application Serial No. 44,644 filed July 20, 1925 50 from which it will be observed that the principal feature of this invention may be utilized in either form of cone contacting member.

This shell or channeled member 1 further 55 has an aperture in the bottom 1^a thereof

midway between the cone contacting devices indicated at 11^a in Fig. 4 and, to secure the stone 12 in place in the holder, I place the holder in a form or mold 13 with the longitudinal edges 15^a of its side flanges 1^b 70 engaging gage faces 15 thereof as indicated diagrammatically in Figs. 4 and 6. In the form or mold has previously been positioned the stone 12 which also lies with its longitudinal outer or working face 12^a on a gage 75 face 14 of the form or mold exactly parallel with the gage faces 15 of the form. Due to the two side edges 15^a of the channel member being finished to a definite length from the outer side of the bottom 1^a, the face 12^a 80 of the stone 12 is parallel with said bottom. In the position of the parts shown in Fig. 4 the stone and the holder are therefore in a relationship in which they are to be fixed and to fix these parts together I introduce a 85 solder or other self-hardening material 13^a through the aperture 11^a. The inaccuracies in stone thickness shown at 12^a in Fig. 5 are thus disposed within the holder and the face 12^a of the stone lies parallel with the side 90 edges 15^a and bottom of the holder at exactly a right angle to the axes of the pins 3 and 4.

The assembled abrasive and holder is then removed from the form and the pins 3 and 4, or the cone contacting member of whatever 95 form, are finished off for contact with the adjusting cones at an exact length measuring from the face of the stone. If pins be utilized for the cone contacting members, as is herein shown, and due to the edges 15^a of 100 the channeled member being finished off parallel with the bottom of the said member against which the shoulder of the pins engages, the axes of the pins are therefore, by this method, exactly at a right angle to the 105 face of the stone. This accuracy in relationship of the stone and holder is necessary in order to secure precision in operation of the tool and to function with the adjusting means so that the faces of all the stones cut 110 the same circle.

The object of the invention therefore is secured by this method and character of device—that is, by this form of holder and method of making thereof I secure precision 115 and secure a grinding tool that is accurate in the finishing of a piece of work and accurate throughout all of its possible adjustments.

I am aware of other devices of this general 120 character in which abrasive members are utilized many of which have stones and holders that are spring projected to working contact with the wall of the aperture being ground. This tool operates differently in 125 that the holders are positively held in the adjusted position, and while the cone members 6 and 7 may traverse or move as a unit longitudinally of the tool body and thus permit the abrasive at one end to move toward

the axis of the tool and at the other end outwardly therefrom as is set forth in the above mentioned pending application, yet as the tool in its operation is relieved from pressure through the grinding away of the surface operated on the adjusting unit including the said cones takes the neutral position shown in Fig. 1 in which the faces of the stones lie exactly parallel with the axis of the tool. This position being assumed at the completion of the grinding operation as the tool grinds free, the aperture being ground through reciprocation and rotation of the tool therein is of a uniform diameter throughout its length and with a straight wall. This accuracy in operation is secured by the character of the holder herein disclosed and the absorption of possible inaccuracies by means of a fluid medium 13^a flowed or floated between the holder and the stone.

The combined abrasive and holder therefore provide a unit to replace worn units of like character and has been devised to avoid inaccuracies resulting from the user of the tool attempting to replace a worn stone in holders as heretofore utilized in this art.

To secure precision in operation of the tool, the unit should be replaced by a new unit of the same accuracy and precision as the worn unit.

By gaging the longitudinal face of the stone and the longitudinal edges of the base or holder in parallelism on the mold the stone and holder may be secured together by self hardening material in a technically correct position relative to each other and the guide pins and the co-operating parts on the body regardless of any irregularities on the back of the stone, as shown at 12^b in Figs. 5 and 6.

It will be noted that this combined abrasive and holder permits of ready replacement of similar articles used in a cylinder grinder in that the stone supporting base provides means for determining and maintaining a desired relation of the abrading surface carried thereby to the axis of revolution and traverse of the cylinder grinder, and that the grinding stone or abrasive is secured to the base by a substantially rigid adherent material which permanently positions the stone with reference to the base and with its abrading surface in said determined position, so that on assembly in the tool the working face of the stone occupies a technically correct working position.

Having thus fully described my invention, its utility and mode of operation, what I claim and desire to secure by Letters Patent of the United States is—

1. As a new article of manufacture, a combined abrasive and holder therefor adapted for replacement of similar articles

used in a cylinder grinder such as described 65 comprising a channeled member and a grinding stone or abrasive secured in the channel by means of a solder and with the face of the stone parallel with the back of the channel member, guide pins secured to the back of the member each having its axis at a right angle to the said back and finished to an equal length from the face of the stone.

2. A combined abrasive and holder therefor adapted for replacement of similar articles used in a cylinder grinder such as described comprising a channeled stone supporting base providing means for determining and maintaining a desired relation of an 75 abrading surface carried thereby to the axis of revolution and traverse of the cylinder grinder, and a grinding stone or abrasive secured in the channel of said base by means of a substantially rigid adherent material 80 permanently positioning the stone in the said channeled member with its abrading surface in said determined relation whereby on assembly in the tool the working face of the stone occupies a technically correct working 85 position.

3. A combined abrasive and holder for cylinder grinders comprising a stamped sheet metal holder of channeled form having integral lugs at its opposite ends for a retaining element, a pair of guide pins extending from the back thereof, and an abrasive or stone secured in the holder by a hardened fluid adherent material permanently positioning the working face of the abrasive or 95 stone at a right angle to the longitudinal axes of the pins, said pins having their free ends finished in like form to equal length from the working face of the stone.

4. A combined abrasive and holder therefor adapted for replacement of similar articles used in a cylinder grinder such as described, comprising a stone supporting base providing means for determining and maintaining a desired relation of an abrading 105 surface carried thereby to the axis of revolution and traverse of the cylinder grinder; and a grinding stone or abrasive secured thereto by means of a substantially rigid adherent material permanently positioning the stone with reference to the base with its abrading surface in said determined relation, whereby on assembly in the tool the working face of the stone occupies a technically 110 correct working position.

5. A combined abrasive and holder therefor adapted for replacement of similar articles used in a cylinder grinder such as described, comprising a stone supporting base and parallel guide pins projecting transversely from the outer side of the base, said base and pins providing means for determining and maintaining a desired relation of an 115 120 125

abrading surface carried thereby to the axis of revolution and traverse of the cylinder grinder; and a grinding stone or abrasive secured to the base by means of a substantially rigid adherent material which permanently positions the stone on the base and with its abrading surface in said determined

relation, whereby on assembly in the tool the working face of the stone occupies a technically correct working position.

10

In testimony whereof I sign this specification.
